(57) **CLAIM**

The ornamental design for a combined seawall and pilaster repair device, as shown and described.

DESCRIPTION

FIG. 1 is a left perspective view of a first embodiment of the subject seawall and pilaster repair device.

FIG. 2 is a right perspective view thereof.

FIG. 3 is a top view thereof.

FIG. 4 is a front view thereof.

FIG. 5 is a left perspective view of a second embodiment of the subject seawall and pilaster repair device.

FIG. 6 is a right perspective view thereof.

FIG. 7 is a top view thereof; and,

FIG. 8 is a front view thereof.

The broken lines shown in FIGS. 1-8 illustrate environment and form no part of the claimed design. The broken lines showing the circular objects on the repair device in FIGS. 1-6 and FIG. 8 illustrate portions of the combined seawall and pilaster repair device and form no part of the claimed design. The dash-dot lines on the left and right sides of the seawall shown in FIGS. 1-8 illustrate boundary lines and form no part of the claimed design.

1 Claim, 8 Drawing Sheets
